DOUBLE STUDY CARRELL UNIT

John L. Gianfagna, Marietta, Ohio, assignor to Sperry Rand Corporation, New York, N.Y., a corporation of Delaware

Continuation-in-part of design application Ser. No. 9,036, Oct. 18, 1967. This application June 4, 1968, Ser. No. 12,554

Term of patent 14 years

Int. Cl. D6—01

U.S. Cl. D33—11

FIG. 1.

FIG. 2.

FIG. 3.

FIG. 4.

FIG. 5.

FIG. 6.

FIG. 7.

FIG. 8.

FIG. 1 is a front perspective view of a double study carrell unit showing my new design;

FIG. 2 is a top view thereof;

FIG. 3 is a rear elevational view thereof;

FIG. 4 is an elevational view taken from a side thereof;

FIG. 5 is a front perspective view of a second embodiment of my new design for a double study carrell unit;

FIG. 6 is a top view of the FIG. 5 embodiment;

FIG. 7 is a rear elevational view of the FIG. 5 embodiment; and

FIG. 8 is an elevational view taken from a side of the FIG. 5 embodiment.

This application is a continuation-in-part of design application No. De. 9,036, filed Oct. 18, 1967, and now abandoned.

I claim:

The ornamental design for a double study carrell unit, substantially as shown and described.
